UNITED STATES PATENT OFFICE.

ARTHUR A. KRAEUTER, OF SOUTH ORANGE, NEW JERSEY.

DESIGN FOR A PRESS FOR TENNIS-RACKETS.

56,525.

Specification for Design.

Patented Nov. 2, 1920.

Application filed April 7, 1920. Serial No. 372,085. Term of patent 14 years.

To all whom it may concern:

Be it known that I, ARTHUR A. KRAEUTER, a citizen of the United States, residing at South Orange, in the county of Essex and State of New Jersey, have invented a new, original, and ornamental Design for a Press for Tennis-Rackets, of which the following is a specification, reference being made to the accompanying drawings, forming part thereof.

In the drawings Figure 1 is a plan view, and Fig. 2 is a side view looking up on Fig. 1 of a press for tennis rackets embodying my design.

I claim:

The ornamental design for a press for tennis rackets as shown.

A. A. KRAEUTER.
